UNITED STATES PATENT OFFICE

151,377

DESIGN FOR A COMBINED LOUD SPEAKER AND SHELTER THEREFOR

Ernoll Wayne La Barre, New York, N. Y., assignor
of one-half to Herbert C. Leech, doing business
as Herbert C. Leech Illustrators, New York, N. Y.

Application March 20, 1947, Serial No. 137,773

Term of patent 7 years

(Cl. D26—14)

To all whom it may concern:

Be it known that I, Ernoll Wayne La Barre, a citizen of the United States of America and a resident of New York, in the county of New York and State of New York, have invented the new, original, and ornamental Design for combined Loud Speaker and Shelter therefor, of which the following is a specification, reference being had to the accompanying drawing, forming part thereof, in which

Fig. 1 is a perspective view of a combined loud speaker and shelter therefor, showing my new design, the dot and dash lines being only for illustrative purposes.

Fig. 2 is a front view of a shelter, embodying my design.

Fig. 3 is a detailed perspective view of the front of the speaker.

I claim:

The ornamental design for a combined loud speaker and shelter therefor, as shown and described.

ERNOLL WAYNE LA BARRE.
